PORTABLE YARDING AND CUTOFF
SWING-SAW MACHINE

Glen A. Johnson, Tenino, Wash.

Application May 29, 1946, Serial No. 672,963

3 Claims. (Cl. 143—46)

1

This invention relates to portable yarding and cut off machines and is particularly adapted to be used in the smaller logging and sawmill operations.

The primary object of the invention is to mount a hoisting unit upon a frame, together with a cut off saw driven by a power plant located on this said frame. This frame is mounted upon wheels so that the entire assembly can be moved about to different timber locations.

With my new and improved yarding and cut off saw mounted upon a portable frame, which in turn is mounted upon wheels, the entire unit can be moved at a minimum of cost.

These and other incidental objects will be apparent in the drawings, specifications and claims.

Referring to the drawing:

Figure 1 is a plan view of my new and improved portable yarding and cut off machine. In this view I have removed the covering or canopy for convenience of illustration.

Figure 2 is a side elevation of the machine taken from the log handling side of the machine.

Figure 3 shows the opposite side of the machine illustrating the power drive mechanism.

Figure 4 is an end sectional view, particularly drawn to illustrate the cut off mechanism, taken on line 4—4 of Figure 2.

Figure 5 is an end sectional view made to illustrate the forward end of the machine, particularly the hoisting drum for operating a boom, same taken on line 5—5 of Figure 2.

Figure 6 is a fragmentary sectional detail of the log push bar mechanism, parts broken away for convenience of illustration, taken on line 6—6 of Figure 1.

Figure 7 is a fragmentary sectional view illustrating the mechanism for operating the friction clutch employed in the operation of the log push bar, the same taken on line 7—7 of Figure 1.

Figure 8 is a fragmentary end view of the driving mechanism for the hoisting drums, taken on line 8—8 of Figure 3.

In the drawings.

My new and improved yarding and cut off machine consists of a frame 1 mounted upon the wheels 2 through the axle 3 secured to the frame by holding brackets 4. Superimposed upon this frame is a sub-frame 5, which is mounted on one side of the main frame, best illustrated in Figures 1 and 4. Superimposed on this sub-frame on the forward end thereof is a third frame 6. This frame is in turn mounted upon the wheels 7, which in turn are journaled to the pedestal 8. The pedestal 8 is rotatable about its vertical shaft 9, Fig. 5, which is journaled within a bearing sleeve 10 secured to the cross plates 11, said plates forming part of the frame 6. A tongue 12 (Fig. 2) is pivotally mounted to the pedestal 8 at 13. This tongue may be hitched to a tractor for the moving about of the machine. I find that by mounting

2

the machine on a three-wheeled chassis greater maneuverability is possible, but I do not wish to be limited to the exact chassis as illustrated.

My invention further consists of mounting the hoisting unit, indicated in general by 14, on one end of the frame of the machine and to one side. This hoisting unit consists of a suitable framework 15, having the drums 16, 17 and 18 mounted thereon by bearings 19. These drums are of well known type, consisting of the drums proper each having a clutch 20 cooperating with a corresponding one of their ends and operated by the cranks 21. A brake drum assembly is indicated at 22 and operated by the usual brake levers 23. The clutches 20 are driven by the drive chain 24 (Fig. 3) through the sprockets 25. The chain 24 is driven by the sprocket 26, Fig. 1, which is keyed to the shaft 27 of the gear box 28. The drive for the gear box will be described later on.

The drum 30 is considered as the hoisting drum while the drum 31 is used for the haul back line in the logging operation. I have provided a drum 32 for pulling the logs through the yarder to the cut off saw, the operation of which will be described later.

Mounted upon the sub-frame 5 is a power plant 33 having a transmission 34. The drive shaft 35 from the transmission 34 enters a gear box 36, which drives the shaft 37 running longitudinally of the frame of the machine. This shaft is mounted within suitable bearings 38. The drive shaft 35 extends through the gear box 36 and into the gear box 28 driving the shaft 27 and the chain 24 as above referred to.

Pivotedly mounted to the main frame of the machine is a boom 39 through which the cables from the hoisting drums can be run at 40 in the performance of the yarding operation of the machine. The upper end of the boom is supported by the cables 41 from a hoist 42. Mounted upon the forward end of the machine is an A-frame 43, whose upper end has a sheave 44 over which the cable 41 is trained from the hoist 42 to the boom 39. The hoist 42 is of the usual construction, having the clutch assembly 45 operated by the lever 46 and also a brake drum 47 controlled by the lever 48. This construction, as stated above, is of well known practice. The hoist 42 is driven by the chain 49 from the power shaft 37. The hoisting unit 14 and the boom 39, together with the hoist 42 makes up the yarding or log hauling feature of my new and improved yarding and cut off machine.

I will now describe the operation and construction of the cut off feature of the machine. A saw 50 is mounted to the arbor 51, which is journaled within suitable bearings 52 to the saw frame 53, said frame is pivotally mounted to the drive shaft 37 by bearings 54. This frame and the weight of the saw is counter-balanced by the extension 55, which may have a counter-balancing material such as concrete 56 therein.

The saw is driven by the chain 51 from the drive shaft 31. This completes the cut off feature of my machine.

I have also provided a log pusher bar 58, which is slidably mounted cross wise the sub-frame 5 through the guide tube 59. This pusher bar is moved transversely of the machine by the action of the drive sprocket 60 cooperating with the rack 61, which may consist of a chain welded to the I-beam, which is known as the pusher bar 58. The sprocket 60 is keyed to the shaft 62, which in turn is driven by the chain 63 through the sprocket 64 by the counter shaft 65 journaled within suitable bearings 66 (Figs. 2 and 6) to the cross frames 67. The counter shaft 65 has a friction wheel 68 keyed thereto and is driven in one direction from shaft 37 by either the belt 69 trained on wheel 68 and a friction wheel 70 fixed on shaft 37, or in a reverse direction, directly against the friction wheel 70.

The end 71 of the counter shaft 65 is mounted within a bearing 72, which is slidably mounted upon the cross frame 67. The bearing 72 may be shifted either way by the link 73 (Figs. 1 and 7), which is pivotally connected thereto at 74 on its one end and to the crank 75 at its opposite end, said crank being keyed to the short longitudinal or cross shaft 76 journaled to the cross frames 67 and operated by the lever 77. When the lever is moved away from the operator standing at the location 78, Fig. 1, the bearing 72 will push the friction wheel 68 towards the friction wheel 70 loosening the belt 69 and driving the friction wheel 68 and the counter shaft 65 in the same direction, together with its sprocket 60 which forces the push bar 58 in the direction of the arrow, the object of which will be described later. When the lever 77 is pulled towards the operator it will tighten the belt 69 causing the said belt to drive the friction wheel 68 in the opposite direction, causing the push bar 58 to travel in the opposite direction of the arrow, referring to Figure 6, back to its starting position.

I will now describe the operation of my yarding and cut off machine, as the machine is brought to location a skid-way 81 shown in broken lines, Figure 2, is abutted against the end of the frame of the machine at 79. The cable 80 trained about the drum 32 is then attached to the rear end of the log to be brought up on the skid-way 81, this log is brought endwise into the machine, as indicated by the broken line 82 in Figure 4, namely in between the sides of framework 15 of the hoisting unit 14 and under the drums 30, 31 and 32 in the pathway for the logs to be handled in the machine upon the platform 83, which consists of a plate 84 welded flush with the top of the frame 1. The log is progressed over the top of this platform towards the bumper 85, Figs. 2 and 3, which is mounted to a longitudinal horizontal beam 86, this beam is slidably mounted through the cross frames 87 of the main frame 1 at 88 and under the platform 83. See Fig. 5. The position of the bumper 85 determines the length of the cut off portion of the log and this bumper is adjustable by having a locking pin 89 passing through the frame 1 and through the holes 90 of the beam 86.

When the log strikes the bumper 85 it will be stopped and the cable 80 can be released from this log and attached to the outboard end of the next log following on the skid-way, which will be brought up against the proceeding log above

described, forcing the same over the platform while it is being cut to lengths and so on thereafter with the following logs. When the log strikes the bumper the handle 91 of the saw assembly is grasped by the operator and the saw is lowered through the log. After it has completed the cut the operator grasps the lever 77 forcing the same away from him, causing the above described power transmission mechanism to move the push bar 58 in the direction of the arrow indicated in Figure 6, which pushes the cut off portion of the log off of the platform 83 and the horizontal support 86 on to a skid-way 92, shown in broken lines (Fig. 1).

This skid-way may consist of ordinary skids or elevating chains into the saw mill, such as I have covered in a co-pending application. After the push bar has removed the logs on to the skids it will be returned as above described by pulling the lever 77 towards the operator reversing the direction of the drive.

When the machine is used for yarding in the logs from over the logging area the operator stands on the platform 93 (Figs. 1 and 4) from where he controls the yarding operation through the hoisting mechanism 14 by the control levers 21 and 23, and as stated above the hoisting and hold back cables 94 are operated from the drums 30 and 31, these cables may extend directly out of the machine as indicated in the drawing, or they may be trained up over the pulleys 40 as indicated in broken lines, Fig. 2, depending upon the type of work to be performed.

When the operator is standing on the platform 35 at 78 he can control the drum 32 which is bringing the logs in over the skid-way 81 from the point that they were brought to by the yarding operations by the control rod 95 which controls the clutch mechanism in the drum 32 by the lever 96. Normally the motor 33 operates the hoisting drum chain 24 continuously, also the drive shaft 37, although the speeds can be varied through the transmission 34 controlled by the clutch control lever 97 and gear control lever 98 located adjacent the operator's platform 78.

As the primary object of my invention is to mount the hoisting and the cut off units, together with their power supply, upon a portable frame, which in turn is mounted upon wheels 2 and 7, it becomes necessary to fold some of the equipment while moving the machine about.

The platform 93 is mounted upon and forms part of the beams 99, whose inner ends 100 pass through the frame 1 and into the pockets 101 which provides a support for the platform 93. See Fig. 4. The roof 102 is hingedly secured to the stationary roof or canopy 103 at 104, being supported by the upright post 105 upon the platform 93.

When a move is to be made the post 105 is removed and the roof 102 hinged downwardly alongside the hoisting unit 14, then the platform 93 and the beams 99 are removed from the pockets 101 and placed on the platform 78. The hinged platform 107 is hingedly secured to the platform 84 at 106 and is folded up while moving the machine.

I do not wish to be limited to the exact mechanical structure as illustrated, as other structural equivalents may be substituted still coming within the scope of my claims.

I claim:

1. In a portable yarding and cut-off machine, a portable frame, a stationary platform thereon, a longitudinal pathway on one side of the plat-

form for the logs to be handled in the machine, manually controlled means above the pathway at one end of the frame and platform for drawing a log into and lengthwise of the pathway upon the platform below said means, a stop adjustably mounted longitudinally in the frame beneath the platform and projecting above the same at the opposite end of the frame to limit the advanced position of the log, a saw mounted on the frame and platform at one side of the pathway and movable into the pathway for cutting the log transversely in the limited position resulting from the contact of the log with the stop, a pusher bar reciprocably supported above the platform to extend transversely thereof and having a longitudinal rack, a shaft journaled on the platform and having a fixed sprocket meshing with the rack, a counter shaft journaled on the platform and having a driving connection to the first shaft at one end, a slideable bearing for the opposite end of the counter shaft, a friction wheel fixed to the countershaft, a driven shaft journaled on the platform, a small friction wheel fixed on the latter shaft in line with the first friction wheel, a belt loosely trained around said wheels, and means connected to the slideable bearing to move the same and the first friction wheel in opposite directions to engage the second wheel or disengage therefrom and tighten the belt, to project the pusher bar against the cut-off portion of the log to discharge same from the opposite side of the platform and to retract the pusher bar at the inside of the pathway.

2. In a portable yarding and cut off machine, a main frame having a fixed platform thereon, a longitudinal pathway on the platform along one side for the logs to be handled in the machine, a manually controlled hoisting unit supported on the frame spaced above the platform pathway at one end for drawing a log onto the platform lengthwise of the pathway below said hoisting unit, a hoisting unit on the opposite end of the frame, a power unit on the frame at one side of the first hoisting unit and pathway and having a horizontal longitudinal shaft along said side driven by said unit and operatively connected to the hoisting units at opposite ends for driving the same, a stop adjustably mounted longitudinally in the frame beneath the platform and projecting above the same at the end opposite the first hoisting unit to limit the advanced position of the log in the pathway, a saw frame pivoted on said shaft and counterbalanced outwardly of the pivot, a circular saw journaled at the free inner end of the saw frame and driven from the shaft for cutting the log transversely in the limited position when the advanced end thereof contacts with the stop, and a log pusher bar mounted on the platform at the same side as the shaft in advance of the saw and reciprocable across and over the platform and pathway and driven from said shaft to push a cut-off portion of a log from the pathway and platform at the opposite side, said bar having a longitudinal rack, a shaft journaled longitudinally on the platform and having a fixed sprocket wheel meshing with the rack therebeneath, a counter-shaft journaled on the platform and operatively geared at one end to the second shaft, a movable bearing for the opposite end of the countershaft, a friction wheel fixed to the counter shaft, a smaller friction wheel fixed on the first shaft in line with the first friction wheel, an endless belt loosely trained around said friction wheels, and means connected to the movable bearing to move the same and the first

friction wheel in opposite directions to engage the second wheel or to disengage same and tighten the belt, to project the pusher bar against the cut-off portion of the log to discharge same from the opposite side of the platform or to retract the pusher bar at the inside of the pathway.

3. A portable yarding and cut-off machine, a main frame having a fixed platform thereon, a longitudinal pathway on the platform along one side for the logs to be handled in the machine, a manually controlled hoisting unit supported on the frame spaced above the platform pathway at one end for drawing a log onto the platform lengthwise of the pathway below said hoisting unit, a hoisting unit on the opposite end of the frame, a power unit on the frame at one side of the first hoisting unit and pathway and having a horizontal longitudinal shaft along said side driven by said unit and operatively connected to the hoisting units at opposite ends for driving the same, a stop adjustably mounted longitudinally in the frame beneath the platform and projecting above the same at the end opposite the first hoisting unit to limit the advanced position of the log in the pathway, a saw frame pivoted on said shaft and counterbalanced outwardly of the pivot, a circular saw journaled at the free inner end of the saw frame and driven from the shaft for cutting the log transversely in the limited position when the advanced end thereof contacts with the stop, and a log pusher bar mounted on the platform at the same side as the shaft in advance of the saw and reciprocable across and over the platform and pathway and driven from said shaft to push a cut-off portion of a log from the pathway and platform at the opposite side, said stop comprising a longitudinal horizontal beam slidably mounted longitudinally in the frame beneath the platform and pathway along the longitudinal center of the latter and formed at its outer end beyond the platform at the inner side of the second hoisting unit in line with the pathway with an abutment extending above the platform for engagement by the advance end of the log to limit the advance thereof for cutting off same at a predetermined distance in advance of the saw, said beam having a plurality of spaced holes therethrough, a cross frame in the main frame through which the beam is slideable, and a locking pin through one of said frames to engage in any of said holes to hold the beam and abutment in longitudinally adjusted position to regulate the advance of the log and portion cut off.
